UNITED STATES PATENT OFFICE.

WILLIAM E. MAGIE, OF BUFFALO, NEW YORK, AND WALTER FERRIS, OF MILWAUKEE, WISCONSIN.

LEAKAGE-RETURN FOR HYDRAULIC TRANSMISSION.

1,312,701.

Specification of Letters Patent.

Patented Aug. 12, 1919.

Application filed August 3, 1918. Serial No. 248,178.

To all whom it may concern:

Be it known that we, WILLIAM E. MAGIE and WALTER FERRIS, citizens of the United States, residing, respectively, at Buffalo, in the county of Erie and State of New York, and at Milwaukee, in the county of Milwaukee and State of Wisconsin, have invented a certain new and useful Improvement in Leakage-Returns for Hydraulic Transmissions, of which the following is a specification.

Our invention relates to hydraulic power transmission devices such as indicated on the accompanying drawings but we do not wish to limit ourselves to any one particular construction as our arrangement for leakage return herein embodied, with slight modification, is adaptable to other forms of mechanism which are in service as hydraulic power transmissions.

The objects of our invention are to afford ample opportunity for sedimentation of the oil which leaks beyond the pressure circuit before returning same thereto; also to provide means for sufficient de-aeration of the oil or other fluid used; also to afford a mechanism which will produce a pressure higher than atmospheric pressure in returning the working fluid to the pressure circuit, thus reducing the tendency to ebullition in the fluid and retarding the emulsification of the said working fluid; also to provide an arrangement whereby the working fluid used may be conveniently inspected as to its clarity and general condition before and after having passed through the working parts of the machine; also to provide a pumping system actuated by a moving part of the transmission device for returning at least a part of the leakage; also to provide means by which the returned fluids are injected back into the pressure circuit evenly, keeping a constant "head" behind the pressure circuit and avoiding, in doing so, any pulsating or throbbing effect in the working fluid employed.

Our invention is illustrated more or less diagrammatically in the accompanying drawings wherein—

Figure 1 is an end view in part section and with some parts broken away;

Fig. 2 is a section on line 2—2 of Fig. 1 with parts in elevation;

Fig. 3 is a section along line 3—3 of Fig. 2 with parts omitted;

Fig. 4 is an enlarged detail sectional view of pump assembly;

Fig. 5 is an enlarged detail sectional view of the distributing valve block;

Fig. 6 is a section taken on line 6—6 of Fig. 1;

Fig. 7 is a sectional view of the central assembly.

Like parts are indicated by like characters in all the drawings.

C is a casing which contains a main or power pumping mechanism driven by an external source of power through a shaft S. It also contains a stroke changing mechanism whereby the stroke and displacement of the pump may be changed at the will of the operator and the hydraulic motor of similar construction to the pump which motor is driven by fluid discharged by the pump thereby generate power which is transmitted through the shaft S¹.

The pump comprises a driving disk D mounted upon shaft S, a group of pumping plungers actuated by said driving disk, and a multiple cylinder barrel D² into whose cylinders said plungers are fitted, but which is mounted upon a pintle formed upon a sliding pintle block Z, whereby the eccentricity of pintle may be varied.

The stroke changing mechanism comprises the sliding pintle block Z, a stationary cross rail T supporting said pintle block and a hand wheel or other suitable mechanism for controlling the sliding of said pintle block, and consequently varying the stroke and displacement of pump.

The hydraulic motor comprises a stationary pintle formed eccentrically upon the cross rail T and similar to the sliding pintle already alluded to as forming part of the pump, a multiple cylinder barrel D³ mounted upon said stationary pintle and similar to corresponding cylinder barrel of the pump, a set of motor plungers D⁵, and a driven disk D⁴ actuated by the fluid pressure generated by the pump and acting against plungers D⁵ whereby power is generated in said crank disk D⁴ and transmitted by shaft S¹ to which this crank disk is attached.

The preceding parts are not fully indicated in the drawings and are not described in detail as they are parts of a typical hydraulic transmission mechanism and do not comprise any part of the present invention.

The sliding block Z is supported by the stationary cross rail T and has a smooth rail engaging contact face, in which are formed two pairs of communicating elongated ports 41, 43 and 42, 44, which form elements of a double system of ports and passages connecting the main pump with the hydraulic motor, and serving to transmit working fluid. Either port may be under high pressure, the other being under low pressure. A continuous drain groove 45 cut in the face of sliding block Z surrounds ports 41, 43 and 42, 44. This groove intercepts all leakage from the ports, in the sliding faces instead of permitting it to escape into the interior of the casing. An annular groove 46 surrounds each plunger D⁵, intercepting all high pressure leakage past said plunger from interior of cylinder. Each groove 46 communicates through a radial duct 47 with an annular gathering groove 48. Groove 48 has the function of gathering all of the leakage returning through the ducts 47 from the intercepting grooves 46 around the plungers. It has also the function of intercepting leakage escaping laterally (on the right hand as shown in Fig. 7) from the abutting surfaces of revolution between the interior bore of the cylinder barrels D³ D² and their corresponding pintles. Groove 55 is located symmetrically with groove 48 but on the opposite side of the central plane of the cylinder barrel, and serves to intercept leakage escaping laterally (toward the left hand as shown in Fig. 7) between the abutting ported surfaces of the cylinder barrels upon the pintles. This leakage is returned to the duct 49 through duct 56. The ducts 49, 50 and 56 connect grooves 48 and 55 with groove 45, these grooves forming a closed system receiving only oil which has leaked past working surfaces under pressure. Two ducts 51 and 52 conduct this leakage into two check valves 53, 54 opening respectively into the ports 43 and 44.

The high pressure existing in port 43 or 44 respectively will close check valve 53 or 54 respectively leaving corresponding check valve 54 or 53 respectively free to open and permit leakage in gathering grooves to return directly by its own pressure and without pumping or other mechanical assistance into the main circuit.

The casing C is closed by the end heads E and E¹ having respectively the integral extensions or hubs H and H¹ for the mounting of suitable bearings for the centrally located shafts S and S¹.

The end head E is formed with a divided reservoir R to contain a portion of the working fluid which for the moment is not within the active fluid circuit of the power transmission, but is in reserve. This reservoir is integral with end head E and surrounds hub H in annular form, the hub passing through

the annular reservoir and serving in connection with partition X and its enlargement B to divide reservoir into two sections 10 and 11 which communicate with each other only over the upper part of hub H. This construction permits the introduction of oil into the lower part of compartment 10 as hereinafter described, and the removal of said oil from reservoir through an opening in the lower part of compartment 11 thus compelling all oil so removed to pass over the upper edge of hub H where it can be inspected before reentering the main circuit. Overflow pipe 12 as hereinafter described determines the oil level in reservoir R and inspection at this point will also reveal deficiency of the proper amount of oil in the apparatus, as in such case oil level will be below top of overflow pipe.

A catch basin R¹ is formed in the bottom of casing C by a curved partition P which closely conforms to the periphery of the disks D and D¹. This partition P makes a tight junction with the ends of main casing but openings R² are left at the sides of the casing through which oil may enter the catch basin.

The machine is charged with a quantity of oil sufficient to fill the working cylinders and their communicating ports and passages, to fill the reservoir R up to the top of overflow pipe 12 and to fill the catch basin R¹ to a point below the upper edges of partition P. As oil leaks into casing from the main circuit of the machine it is immediately replaced by an equal quantity of oil forced in as hereinafter described by pump G. This leakage replacement is taken from compartment 11 of reservoir R and is immediately replaced by an equal amount of oil flowing across top of hub H from left to right. A somewhat larger quantity of oil is simultaneously pumped through a different set of passages by same pump G from catch basin R¹ into the lower part of compartment 10 of reservoir R. This larger quantity of oil rises slowly through the left hand compartment 10 of reservoir to the surface in the neighborhood of upper end of overflow pipe 12 and divides into two parts; an amount exactly equal to the amount simultaneously withdrawn from compartment 11 to supply leakage from the power circuit passes over the top of the hub H on the right hand side of reservoir, while all excess above said amount flows into the top of the overflow pipe 12 and returns into the catch basin through port 13, to be again pumped up by the pump assembly G as hereinafter described.

The pump G really comprises two separate pumps having the common plunger 2 closely fitted in the pump cylinder as shown, and provided with a reduced tubular extension 3 closely fitted in a reduced bore at

the upper end of said pump cylinder. Tubular extension 3 is pin connected to a rod 4 which engages a crank pin formed on the end of crank shaft 5 to which shaft is keyed gear wheel 8 meshing with gear wheel 9 which is secured to main pump shaft S. Therefore the pump G is continuously operated so long as the power pump is in operation. The two separate parts of the 10 pump in this assembly are the circulating pump and the leakage return pump.

Circulating pump G¹ is formed by the lower end of plunger 2 coacting with the lower end of the pump cylinder, taking in 15 oil through inlet opening 1 from reservoir R¹ and discharging through check valve V and passage through tubular plunger extension 3 into crank case 6 and thence through port 7 which terminates in bottom 20 of compartment 10 of reservoir R.

The leakage return pump is formed by the upper end of the plunger 2 coacting with the upper part of the pump cylinder bore taking in oil through the passage 14 communicating with lower part of compartment 11 25 of reservoir R on the right hand side of partition X, and discharging through port 15, check valve 17 and pipe 16. Pipe 16 divides into a leakage return pipe 30, which supplies 30 to the main power circuit the exact amount of make-up oil required, and the side branch 21 which discharges into reservoir R through relief valve body 22. Through this relief 35 valve a predetermined pressure is maintained on a leakage return system and the excess oil not required to make up the deficiency caused by leakage is returned to reservoir R to be again circulated.

The intake passages 1 and 14 respectively 40 of the circulating pump G¹ and the leakage return pump G² respectively are opened and closed by the travel of the pump plunger 2, each intake port being opened as the plunger approaches the end of the corresponding suction stroke and closed soon after the plunger starts on its return or delivery stroke; after which closure of the intake port the remaining fluid is expelled through the delivery check valve V or 17 respectively

45 As already described the main power pump and the motor are connected by a closed system of ports, one side of the system carrying high pressure fluid from pump to motor and the other side carrying back to the 50 pump low pressure or return fluid exhausted from the motor. When the hydraulic motor is reversed in direction the two sides of this closed port system interchange their functions, the former pressure port becoming 55 the return port and vice versa. In Fig. 7, 32 indicates the port which is functioning as pressure port and which is at all times connected through passage and pipe 20 with the top side of distributing valve casing 18. 60 65 31 indicates the port functioning as low

pressure or return port and connected through passage and pipe 20 with the right hand end of valve casing 18. As already mentioned leakage return pump G² is continuously forcing oil into the two pipes 21 and 70 75 30. Pipe 21 is connected to relief valve assembly whose construction will be described later and which serves to maintain a predetermined low or return pressure in the entire piping system connected with the discharge check valve 17 of this leakage return pump. Relief valve 22 also serves to return into reservoir R all of the excess oil delivered by leakage return pump above the amount which which can pass into distributing 80 valve 18 through leakage return pipe 30, are drilled through the shell of casing 22 to permit the escape into the reservoir of any fluid which passes valve seat 24.

Oil can only pass into valve seat by 85 pushing the stem 26 to the right against the spring force until the left hand edge of plunger portion 31 passes the corner of the valve seat 24. The valve then begins to open and further compression of the spring 90 will enlarge the annular opening so much as to permit the escape into reservoir R of any excess in the delivery of leakage return pump. During the in-take or downward stroke of leakage return pump G² no fluid is 95 being delivered through check valve 17, and therefore the pressure against fluid in pipe 30 and its connecting passage to port 31 would be permitted to fall momentarily unless other means than the leakage pump were 100 supplied to avoid this. This function is supplied by the plunger portion 31 of relief valve which continues its motion toward the left should there be any fall in pressure in pipe 21 after edge of plug 31 has passed 105 corner of conical valve seat. In this way relief valve plunger acts as an auxiliary pump plunger supplying momentarily the leakage from port 31 during each suction stroke of the leakage return pump and thus 110 maintaining an even flow of returned leakage under continuous pressure.

The use and operation of our invention are as follows:

The amount of power which may be 115 transmitted by a hydraulic transmission of the type herein described is directly proportional to the speed at which the machine can be run, and to the pressure which it will endure in the main oil circuit. This pressure 120 is a function of the strength of the various parts, but the speed attainable depends principally upon the effectiveness of the devices for returning to the main oil circuit the oil which leads therefrom past the various 125 working surfaces. In most hydraulic transmission machines the amount of this leakage which escapes into the casing increases rapidly with rising operating pressure, and the leakage return pump or other device has 130

to have sufficient capacity to return the maximum amount of leakage which occurs at the highest operating pressure. In the present device this increase of leakage into 5 the casing with rising operating pressure is obviated by the intercepting grooves 46 around the various plungers, 45 around the abutting ports, and 48 and 55 around the interior bores of the cylinder barrels. All of 10 the leakage from the ports, working cylinders, etc., subjected to high pressure is caught by the above described intercepting grooves and directly returned through either of the check valves 53 or 54, as the 15 case may be, into that port (43 or 44 as the case may be) which is conducting the exhaust fluid from the hydraulic motor back to the intake port of the main pump, and is hence subjected only to low or return 20 pressure.

The only fluid which leaks out into the casing is such as is forced past the abutting surfaces 60, 61, 62, 63 between the various working parts exterior to the various intercepting grooves. As all of these intercepting grooves are filled with fluid at the return or low pressure which is almost constant, the quantity of this leakage into the casing is small because the pressure is low 25 and practically constant because the pressure is constant. The leakage return pump G² may therefore be much smaller than the prevailing forms of hydraulic transmission and will always be running at approximately 30 its full capacity as it does not have to take care of peak loads of excessive leakage during 35 periods of maximum working pressure.

Oil leaking from the main pressure circuit, cylinders, etc., of the main pump and 40 hydraulic motor is either thrown outward against the top end walls of casing C or falls downward into the curved depression above partition P. The part which strikes the walls may drain directly down into 45 catch basin through openings R². The part which strikes the cover may fall down on top of partition P. All oil gathered in partition P is continuously wiped up by disks D and D¹ and thrown outward, striking the 50 walls and draining down into the catch basin R¹. Thus all of the direct leakage is finally drained into the catch basin, where it is comparatively quiet. Sedimentation is thus assisted, most of the solid matter being 55 deposited on the bottom of the catch basin as a sludge. Entrained air also tends to be disengaged from the oil coming to the surface in the catch basin.

Circulating pump G¹ continuously draws 60 from the comparatively quiet oil in the catch basin an amount greater than is necessary to supply the maximum leakage requirement. This oil is delivered into compartment 10 of reservoir R and slowly rises to the surface. 65 During this process further sedimentation

occurs and further entrainment of air, the latter escaping in bubbles at the surface. Simultaneously leakage return pump G² is continuously drawing from compartment 11 a less quantity of oil than is being continuously pumped into compartment 10 from catch basin. In the construction here shown the less displacement necessary for pump G² is secured by using the upper part of pump chamber for this function, the displacement per stroke being reduced by the cross section of tubular extension 3. On account of the excess capacity of circulating pump G¹ reservoir R is always kept full to the overflow point, any variations in quantity of total oil contained in the machine appearing as variations in level of oil in the catch basin. Consequently the compartment 11 is always kept full to supply the leakage return pump and a slow circulation of excess oil is maintained downward into catch basin through overflow pipe 12 and upward through pump G¹ into compartment 10, this facilitating a continuous process of sedimentation and de-aeration of the working fluid.

We claim:

1. In a hydraulic transmission comprising a pump, a motor, and an oil circuit connecting and including them having both high and low pressure branches, means for intercepting leakage from the high pressure system and automatically returning it to the low pressure system together with separate means for positively supplying make-up oil to the low pressure system under pressure.

2. In a hydraulic transmission comprising a pump, a motor, and an oil circuit connecting and including them having both high and low pressure branches, means for intercepting leakage from the high pressure system and automatically returning it to the low pressure system together with separate means for positively supplying make-up oil to the low pressure system under pressure, an automatic pressure release adapted to permit escape of said oil when the pressure in the low pressure system exceeds a predetermined point.

3. In a hydraulic transmission comprising a pump and motor, an oil circuit connecting and including them having high and low pressure branches, a housing containing them, means for intercepting leakage from the high pressure system before it escapes into the housing, means for conducting such leakage back to the low pressure system and separate means for positively returning oil which has escaped beyond the first intercepting means under pressure back into the low pressure system.

4. In a hydraulic transmission comprising a pump and motor, an oil circuit connecting and including them having high and low

pressure branches, a housing containing them, means for intercepting leakage from the high pressure system before it escapes into the housing, means for conducting such leakage back to the low pressure system and separate means for positively returning oil which has escaped beyond the first intercepting means under pressure back into the low pressure system said means comprising a pump driven from the transmission pump.

5 5. In a hydraulic transmission comprising a pump and motor, an oil circuit connecting and including them having high and low pressure branches, a housing containing all the parts, means for intercepting leakage from the high pressure system, returning it automatically to the low pressure system and separate means for gathering the leakage from the interior of the housing and 15 returning it under pressure to the low pressure system.

20 6. In a hydraulic transmission comprising a pump and motor, an oil circuit connecting and including them having high and low pressure branches, a housing containing all the parts, means for intercepting leakage from the high pressure system, returning it automatically to the low pressure system and separate means for gathering the leakage 25 from the interior of the housing and returning it under pressure to the low pressure system said means comprising a pump driven in unison with the transmission pump.

30 7. In a hydraulic transmission comprising a pump and motor, an oil circuit connecting them and having high pressure and low pressure branches, an empty casing, a catch basin, a reservoir, means for circulating reserve oil between the catch basin and the reservoir 40 and means for forcing back into the oil circuit sufficient oil to replace the leakage therefrom.

35 8. In a hydraulic transmission comprising a pump and a motor, an oil circuit connecting them and having high pressure and low pressure branches, a sedimentation reservoir, an inspection reservoir, means for transferring sedimented liquid to the inspection reservoir and means for returning 45 make-up liquid to the active oil circuit.

50 9. In a hydraulic transmission, means for gathering and returning leakage comprising a reservoir divided into two parts, means for introducing leakage into one of said parts and for drawing make-up oil from the second and forcing it back into the system and means for inspecting said oil during its passage through the reservoir.

55 10. In a hydraulic transmission an empty operating chamber, a sedimentation basin for gathering leakage, means for returning leakage to the active circuit and means for inspecting said returned oil on its way to the leakage return means.

60 11. In a hydraulic transmission, an empty

operating case, a catch basin or sedimentation reservoir, means for conducting to the sedimentation reservoir leakage gathered in the operating case and means comprising a pump for returning said oil from reservoir 70 to main circuit.

12. In a hydraulic transmission having a fluid pump and motor and high pressure and low pressure passages connecting them, a closed duct arranged to intercept leakage 75 from the high pressure side of the oil circuit and to return it to the low pressure side, a chamber arranged to gather all leakage not intercepted by said duct and a pump for returning said secondary leakage from said 80 chamber to the low pressure side of circuit.

13. In a hydraulic transmission having a fluid pump and motor and high pressure and low pressure passages connecting them, a closed duct arranged to intercept leakage 85 from the high pressure side of the oil circuit and to return it to the low pressure side, an operating chamber arranged to gather all leakage not intercepted by said duct and means for returning to low pressure side of the circuit at a pressure above 90 that of the atmosphere said leakage gathered in the operating chamber.

14. In a hydraulic transmission having a fluid pump and motor, and high pressure and 95 low pressure passages connecting them, a closed duct arranged to intercept leakage from the high pressure side of the oil circuit and return it to the low pressure side, a splash chamber arranged to gather all 100 leakage not intercepted by said duct, and means for returning to the low pressure side of the circuit all leakage gathered in the splash chamber.

15. In a hydraulic transmission having a 105 pump and a motor, a drainage groove located between adjacent working surfaces for gathering primary leakage and returning it to the active oil circuit, and a duct connected with a leakage pump for returning secondary 110 leakage.

16. In a hydraulic transmission a combination of a fluid pump and outflow port system, a fluid motor, a return port system for returning fluid which leaks from outflow 115 port system and a pump for returning fluid which leaks from the return port system.

17. In a hydraulic transmission having a fluid pump and motor, and high and low pressure passages connecting them, means 120 for intercepting leakage from the high pressure side and returning it directly to the low pressure side of the oil circuit.

18. In a hydraulic transmission having a fluid pump and motor, and high and low 125 pressure passages connecting them, a passage arranged to intercept the leakage from the high pressure side of the oil circuit and to return it directly to the low pressure side, together with means for gathering all leak- 130

age not intercepted by said passage, and returning it to the low pressure side of the circuit.

19. In a hydraulic transmission having a fluid pump and motor, and high and low pressure passages connecting them, a passage arranged to intercept the leakage from the high pressure side of the oil circuit and to return it directly to the low pressure side, together with means for gathering all leakage not intercepted by said passage, and returning it under pressure to the low pressure side of the circuit.

20. In a hydraulic transmission having a fluid pump and motor, and high and low pressure passages connecting them, a passage arranged to intercept the leakage from the high pressure side of the oil circuit and to return it directly to the low pressure side, together with means for gathering all leakage not intercepted by said passage, and returning it under pressure to the low pressure side of the circuit, comprising, in part, a pump.

25 21. In a hydraulic transmission having a

fluid pump and motor, and high and low pressure passages connecting them, a passage arranged to intercept the leakage from the high pressure side of the oil circuit and to return it directly to the low pressure side, together with means for gathering all leakage not intercepted by said passage, and returning it to the low pressure side of the circuit comprising a pump and passages connected therewith, a liquid storage tank fed by the pump, and a connection between said tank and the low pressure side of the circuit.
